BUTTON OR SIMILAR ARTICLE

Ara Yacobian, 66 Ridge Hill Farm Road,
Wellesley, Mass.

Filed July 12, 1965, Ser. No. 86,108

Term of patent 7 years

(Cl. D17—2)

FIG. 1

The essential features of the design reside in the full-line portions on the drawing.

I claim:

The ornamental design for a button or similar article, substantially as shown and described.
